COMBINED PHONOGRAPH AND FILM STRIP VIEWER OR SIMILAR ARTICLE

Richard Culbertson, New Hartford, and Stuart Mundt,
Clinton, N.Y., assignors to General Electric Company,
a corporation of New York

Filed Mar. 31, 1967, Ser. No. 6,473

Term of patent 7 years

(Cl. D56—4)

FIG.1

FIG.2

FIG.3

FIG.4

FIG.5

FIG.6

FIGURE 1 is a front, top and left side perspective view of a combined phonograph and film strip viewer or similar article in accordance with our new design;

FIGURE 2 is a right side elevational view;

FIGURE 3 is a front elevational view on an enlarged scale;

FIGURE 4 is a top plan view;

FIGURE 5 is a left side elevational view; and

FIGURE 6 is a rear elevational view thereof.

A portion of FIGURES 1 and 3 is diagonally lined to indicate a transparent viewing screen having a diffusing coating thereon suitable for the projection of an image on the screen.

We claim:

The ornamental design for a combined phonograph and film strip viewer or similar article, as shown and described.
